UNITED STATES PATENT OFFICE.

BERNARD H. KERSTING, OF BEN AVON, PENNSYLVANIA, ASSIGNOR TO DRAVO CONTRACTING COMPANY, OF PITTSBURGH, PENNSYLVANIA, A CORPORATION OF PENNSYLVANIA.

DRIVE FOR PADDLE-WHEEL BOATS.

Application filed November 13, 1926. Serial No. 148,222.

This invention relates to a drive for paddle wheel boats and provides an improved gear connection between the power source and the paddle wheel which has been found in 5 actual practice to be very desirable.

Various drives for paddle wheels have been proposed, but most of these have been of such nature that the prime movers had to be placed adjacent the paddle wheels. In 10 small river craft the stern paddle drive is common, and this meant that the engines had to be placed well astern in the boat. For various reasons it is desirable to have the prime movers forward, particularly if 15 internal combustion engines are employed. I therefore provide a drive shaft extending longitudinally of the boat, a paddle wheel shaft, an intermediate shaft substantially parallel to the paddle wheel shaft, spur gear- 20 ing connected to the intermediate shaft with the paddle wheel shaft, and bevel gearing connecting the intermediate shaft with the drive shaft. Preferably, the spur gearing and the bevel gearing are so mounted on the 25 boat frame that there is no opportunity for the gears to get out of alignment and thus decrease the efficiency of operation. This condition is best worked out by providing a housing in which the intermediate shaft and 30 the drive shaft are journaled, the housing being securely mounted in the boat frame in fixed relation to the paddle wheel shaft. The housing is so formed that the gears may be readily assembled, and it also constitutes 35 an oil reservoir. This permits of the mechanism running for months at a time without attention.

Preferably the housing is placed inside the boat buffer so that the inside mechanism is 40 protected from injury. The buffer is provided with a removable portion for ready access to the housing.

For driving stern paddle wheels, I provide a shaft which extends longitudinally of 45 the boat but diverges from the boat axis so that the rear end of the shaft lies to one side of the boat. The rear end of the shaft is connected, preferably through bevel gearing, to the paddle wheel. This arrangement provides a very simple and desirable form of 50 drive.

In the accompanying drawings which il- 105 lustrate the present preferred embodiment

of my invention as applied to a stern paddle wheel boat, —

Figure 1 is a top plan view partly broken away of a boat having my invention applied thereto;

Figure 2 is a side elevation to an enlarged scale, and partly broken away, showing the 60 gear housing;

Figure 3 is a horizontal section taken on the line III—III of Figure 2;

Figure 4 is a vertical section taken on the line IV—IV of Figure 2;

Figure 5 is a side elevation of the gear housing with the cover removed;

Figure 6 is a view similar to Figure 2 but showing a modified structure; and

Figure 7 is a section taken on the line 70 VII—VII of Figure 6.

Referring first to the embodiment of the invention illustrated in Figures 1 to 5 inclusive, there is shown a boat having a hull, indicated generally by the reference character 75 2, and provided with a two part stern paddle wheel 3. Each half of the paddle wheel is mounted on an individual shaft 4. The inner ends of these shafts are carried in a central bearing 5 secured to a central boat 80 girder 6. Their outer ends are carried in bearings 7 secured to longitudinal boat girders 8 which are preferably of the box type.

Each section of the paddle wheel is driven from a separate internal combustion engine 9 located forwardly in the boat, and connected through a suitable clutch 10 to a longitudinally extending drive shaft 11. This shaft is carried in bearings 12 and is provided with flexible couplings 13. The 90 drive shaft terminates in an enlarged portion 14 which is mounted on roller bearings 15 and 16. The bearing 15 is carried in a housing member 17, and the bearing 16 is carried in a cap 18 secured to the housing 95 member 17. Grooves 19 adapted to be filled with grease and a packing 20 are provided around the shaft to prevent egress of lubricant or ingress of water. The housing member 17 lies outside the hull of the boat and 100 it is therefore necessary that the rear end of the shaft 11 project outside the hull. This portion is protected by a pipe sleeve 21 which terminates in the cap 18.

The enlarged portion 14 of the shaft 11 105 carries a bevel pinion 22 which meshes with

a bevel gear 23 carried on a shaft 24. The shaft 24 has a spur pinion 25 formed thereon, this pinion meshing with a spur gear 26 mounted on the shaft 4.

As above stated, the longitudinal girder 8 is preferably of the box type, comprising spaced apart vertical plate members 27 and 28. These plates carry the housing for the gears. The housing member 17 accommodates the bevel pinion 22 and its gear 23. It also forms a cover for a main housing 29. The housing 29 makes a close fit at 30 and 31 with plates 32 and 33 permanently secured to the girder plates 27 and 28, respectively. In assembling the boat drive, the plates 32 and 33 are riveted to the girder plates 27 and 28 and are then machined so as to accommodate the housing 29. The housing is then secured in place by rivets 34, which pass through the girder plate 28, the reinforcing plate 33 and the housing proper.

The shaft 24 is carried in roller bearings 35 whose stationary races are mounted in caps 36 and 37 secured respectively to the housing member 17 and the main housing 29. These caps are machined to make a close fit with the housing members which carry them.

It will be noted that the roller bearings 16 and 35 are all of the well known Timken type, employing tapered rollers. Shims 38 are provided under each of the caps 18, 36 and 37, whereby these bearings may be adjusted. After the bearing wears, a thinner shim may be substituted under the suitable cap, so that this cap, when tightened back into place, will be effective for taking up the wear. It will be noted from Figure 3 that the pinion 22 is mounted between bearings. This arrangement is particularly desirable because it insures that the bevel gears will mesh properly, even though the boat hull should become twisted, thus tending to mis-align the shaft.

The shaft 24 is hollow, as shown in dotted lines in Figure 3, and the caps 36 and 37 are each provided with openings substantially co-axial with the bore of the shaft 24. These openings are ordinarily closed by pipe plugs 39, but if the plugs are removed a clear sight may be had through the housing and the shaft. This arrangement is found to be very desirable in lining up the various parts, not only on initial assembly of the boat, but also at times when repairs are made.

Even in boats of relatively small size, the shaft 24 is quite heavy. It is, of course, necessary to remove the housing member 17 in order that the shaft may be put into place, and until the housing member 17 is replaced, the shaft would ordinarily be very difficult to handle. I provide a pair of lugs 40 which are integral with the main housing 29, and project to a point adjacent the

path described between the tips of the teeth in the pinion 25. By this arrangement, the end of the shaft 24 which lies closer to the center of the boat may be fitted into its bearing and the shaft allowed to rest upon the lugs 40 while the housing member 17 is being replaced. If desired, the plugs 39 may be removed and a bar placed in the opening through the shaft so as to manipulate the same and get it properly fitted into its outside bearing.

As above stated, the housing constitutes a reservoir for a lubricant. It will be seen, however, that the housing, as thus far described, is not large enough to completely enclose the gear 26. I employ the interior of the box girder 8 as a connecting reservoir for a lubricant. The plates 27 and 28 are connected by a cross plate 41 which serves not only as a stiffener, but also as an end wall for the reservoir formed within the box girder 8. The reservoir is connected to the interior of the housing 29 through an opening 42, and also through an opening 43. This latter opening extends far enough around the housing to accommodate the gear 26. This is best shown in Figure 5 where the pitch line of the gear 26 is shown as a chain line.

The portion of the box girder 8 which lies to the left of the cross plate 41, as viewed in the drawings, is filled with lubricant, and the enclosure of the gear drive is completed by a cover 44 which surrounds the upper part of the gear 26. With this construction no water can enter the gear chambers, nor will lubricant escape. By reason of the large lubricant capacity, the apparatus may be operated for months or years without attention.

The boat buffer 45 lies outside the gear housings and is intended to protect the same. The buffer prevents the housings from being broken or the shafts from being bent or misaligned. It is made with a removable portion 46 secured in place by bolts 47. If it is desired to work on the gear drive, the bolts 47 may be removed and the buffer portion 46 is taken out. This permits of readily disassembling the entire gear drive.

Figures 6 and 7 show a slightly modified structure. The drive mechanism remains the same, but special braces are provided for the box girder 8^a. These braces constitute a channel 50 extending from a bracket 51 secured to the boat body 52 and terminating at its lower end between the plates 27^a and 28^a of the box girder 8^a. As shown in Figure 7, the channel 50 is of such width that it fits nicely between the plates 27^a and 28^a and is secured thereto by rivets 53. Preferably the channel 50 terminates in the box girder just above the housing 29^a so as to transmit strains therefrom back to the boat frame.

Figure 6 also shows a strut 54 formed of two angles placed back to back. These angles are riveted to a plate 55 whose lower edge is riveted to one flange of the girder 50. The lower edge of the strut 54 engages the bearing 7^a and not only prevents shifting thereof, but also transmits its load in part back to the boat body 52.

I have illustrated and described a preferred form of invention as applied to a stern wheel paddle boat, but it will be understood that the invention may be otherwise embodied within the scope of the following claims.

15 I claim:

1. A drive for paddle wheel boats, comprising a boxlike boat girder, a drive shaft extending longitudinally of the boat, a paddle wheel shaft extending crosswise of the boat, an intermediate shaft extending crosswise of the boat, gearing connecting the intermediate shaft with the paddle wheel shaft, gearing connecting the intermediate shaft with the drive shaft, and a common bearing member secured to the girder and having bearings for the drive shaft and the intermediate shaft.

2. A drive for paddle wheel boats, comprising a boxlike boat girder, a drive shaft extending longitudinally of the boat, a paddle wheel shaft extending crosswise of the boat, an intermediate shaft extending crosswise of the boat, gearing connecting the intermediate shaft with the paddle wheel shaft, gearing connecting the intermediate shaft with the drive shaft, and a substantially enclosed housing for said gearing, the housing providing a bearing support for the drive shaft and the intermediate shaft.

40 3. A drive for paddle wheel boats, comprising a boat frame, a drive shaft extending longitudinally of the boat, a paddle wheel shaft extending crosswise of the boat, an intermediate shaft substantially parallel to the paddle wheel shaft, spur gearing connecting the intermediate shaft with the paddle wheel shaft, bevel gearing connecting the intermediate shaft with the drive shaft, a common metal support secured to the frame 45 and carrying the drive shaft and the intermediate shaft, and a buffer lying outside the bearing support and adapted to protect the drive mechanism.

45 4. A drive for paddle wheel boats, comprising a drive shaft extending longitudinally of the boat, a paddle wheel shaft lying

crosswise of the boat, an intermediate shaft substantially parallel to the paddle wheel shaft, spur gearing connecting the intermediate shaft with the paddle wheel shaft, 60 bevel gearing connecting the intermediate shaft with the drive shaft, a housing substantially enclosing said gears, and a buffer lying outside the housing and adapted to protect the same from injury.

5. A drive for paddle wheel boats, comprising a drive shaft extending longitudinally of the boat, a paddle wheel shaft lying crosswise of the boat, an intermediate shaft substantially parallel to the paddle wheel shaft, spur gearing connecting the intermediate shaft with the paddle wheel shaft, bevel gearing connecting the intermediate shaft with the drive shaft, a housing substantially enclosing said gears, and a boat 70 buffer, the buffer having a removable portion lying outside the housing.

6. In a paddle wheel boat drive, a paddle wheel shaft lying crosswise of the boat, a second shaft lying substantially parallel thereto and connected to the paddle wheel shaft by gearing, a housing for an intermediate shaft, the housing having a cover adapted to make a bearing support for one 80 end of the intermediate shaft and means for supporting the shaft substantially in its proper position when the cover is removed.

7. In a paddle wheel boat drive, paddle wheel shafts lying crosswise of the boat, co-axial intermediate shafts parallel thereto, the 90 intermediate shafts being hollow to facilitate aligning thereof, and gearing connecting the intermediate shafts with the paddle wheel shafts.

8. In a paddle wheel boat drive, spaced 95 housings and substantially co-axial shafts one within each housing, the shafts being hollow, and the housing being provided with removable closures whereby the openings through the shafts are rendered accessible to 100 facilitate aligning of the shafts.

9. A paddle wheel boat drive comprising a hollow boat girder, a gear housing connected to the girder and having its interior communicating with the interior of the 105 girder, and drive gearing lying in the housing and in the girder, the housing and the girder forming a reservoir for lubricant.

In testimony whereof I have hereunto set my hand.

BERNARD H. KERSTING.
